UNITED STATES PATENT OFFICE

HERSIL L. G. CORNELL, OF MILWAUKEE, WISCONSIN, ASSIGNOR TO THE MILWAUKEE
BRUSH MANUFACTURING COMPANY, OF MILWAUKEE, WISCONSIN, A CORPORATION
OF WISCONSIN

ROTARY BRUSH

Application filed November 11, 1929. Serial No. 406,304.

The invention relates to rotary brushes.

An object of the invention is to provide a rotary brush of simple but effective construction, permitting the use of a large number of bristles within a given space for increasing the life of the brush.

Another object of the invention is to provide a rotary brush including a plurality of bristle-holding rings which are axially compressed in the assembly of the brush to form a dense bristle structure.

A further object of the invention is to provide a rotary brush including a sheet metal hub structure which is of relatively light weight and simple construction and which will permit the brush to be assembled in balanced condition.

The invention further consists in the several features hereinafter set forth and more particularly defined by the annexed claims.

In the accompanying drawings,

Fig. 1 is a side elevation of a rotary brush embodying the invention, parts being broken away and parts being shown in section;

Fig. 2 is a sectional view of the brush taken on the line 2—2 of Fig. 1;

Fig. 3 is an expanded perspective view of the hub, and

Fig. 4 is a perspective view of an adapted for permitting the use of the brush on a smaller shaft.

The hub structure of the brush includes a pair of complementary semi-cylindrical sheet metal members 10, which co-operate to form a cylindrical sleeve and which are provided at their adjacent edges with outstanding flanges 11 disposed in abutting relation. A pair of complementary sheet metal members 12 surround the sleeve-forming members 10 and are provided with inturned flanges 13 at their adjacent ends, disposed in edgewise abutment with the mid-portions of the outer periphery of the sleeve-forming members 10, the outstanding flanges 11 of the members 10 being disposed in edgewise abutment with the mid portions of the inner periphery of the sheet metal members 12, as best seen in Fig. 3. The sheet metal members 12 are each provided with shallow channels 14 extending parallel to the axis of the hub to receive at-

taching members therein, as hereinafter described, and these channels are each arranged substantially midway between the flanges 11 and 13. The hub structure also includes a pair of end clamping plates or disks 15, each of which is provided with a central shaft-receiving opening 16 and a plurality of spaced slots 17 adapted to register with the ends of the channels 14 in the sheet metal hub members 12 to receive therethrough sheet metal attaching members 18. The attaching members 18 include laterally extending end flanges 19 which serve to hold the end clamping disks 15 in abutment with the sheet metal members 10 and 12, as hereinafter described.

A plurality of bristle-holding rings 20 are placed in lateral abutment about the hub members 12 and each ring 20 preferably is of a type in which radially extending bristles 21 are held on a twisted pair of wires.

In assembling the brush one of the end disks 15 is set in a press with the assembled sheet metal hub members 10 and 12 set concentrically thereon and receiving in the channels 14 the attaching members 18, which pass through the slots 17 in the disk and have their flanges 19 abutting on the then lower face of the disk. The bristle-supporting rings 20 are then slipped over the outer hub members 12 and the other end disk 15 is passed over the upstanding ends of the attaching members 18. The brush assembly is then subjected to high pressure to squeeze the bristle-holding rings 20 tightly together to lie within the width of the hub members 12, and the upper ends of the attaching members 18 are then clinched over onto the upper end disk 15 to retain the parts in assembled relation. During the pressing operation the bristle-holding rings 20 tend to become flattened and press inwardly on the hub members 12 to thereby compress both the hub members 10 and 12, which are formed in complementary parts, as above described. The sheet metal hub members 10 and 12 are sufficiently deformable to be urged inwardly during the pressing operation, which distributes the stresses arising during the pressing operation and facilitates the obtaining of a balanced condition of the brush. The bristle-holding

rings 20 are now tightly held in place against shifting and a dense bristle structure is formed by the lateral compression of the bristle-holding rings 20, thereby insuring long service. The end plates or disks 15 are preferably provided with inturned prongs or tongues 22, which extend into the space occupied by the bristles.

The coaxially arranged openings 16 of the end plates or disks 15 are adapted to have a shaft fit therein, which is clamped to the brush in the usual manner. When the brush is to be mounted on a smaller shaft a pair of adapters 23 are fitted into opposite sides of the hub, one of these adapters being shown in Fig. 4. Each adapter consists of a sheet metal plate, which is provided with an in-turned annular flange 24 forming a shaft-receiving opening therein, a plurality of in-turned flanges 25 adapted to fit within the circular opening 16 of the end plate, and a plurality of radially extending projections 26 adapted to engage the outer face of the end plate 15.

Before the brush is placed in service, the radially extending bristles 21 are trimmed at their outer ends to provide a circular periphery.

The invention provides a rotary brush including a light but strong hub structure on which the densely packed bristles and their holding members can be securely mounted without the use of metal calking, such as lead, thereby permitting a balanced condition of the brush to be readily obtained. The close packing of the bristles not only insures long wear but also avoids excessive deflection of the bristles when the brush is in use.

What I claim as new and desire to secure by Letters Patent is:

1. In a rotary brush, the combination of a hub including a plurality of complementary radially yielding members and a pair of clamping disks arranged at the opposite ends of the hub, a plurality of bristle-holding rings carried on said hub members in laterally adjacent relation and including radially-extending bristles, and means for retaining said clamping disks against said hub to hold said bristle-holding rings on said hub in axially-compressed relation to provide a dense bristle structure.

2. In a rotary brush, the combination of a hub having channels extending therealong on its outer periphery in parallel relation to the axis, a plurality of bristle-holding rings mounted on said hub and including radially extending bristles, a pair of clamping plates disposed at opposite ends of said hub, and attaching members connecting said clamping plates for retaining said bristle-holding rings in axial compression, said attaching members

having their intermediate portions disposed in said channels.

3. In a rotary brush, the combination of a pair of complementary inner hub members, a pair of complementary outer hub members surrounding said inner hub members and having their joints offset from the joints of said inner hub members, a plurality of bristle-holding rings carried on said outer hub members and including radially extending bristles, end clamping plates and means for retaining said end clamping plates against said hub members to hold bristle-holding rings on the hub structure in axially-compressed relation to provide a dense bristle structure, the axial compression of said bristle-holding rings urging said hub members inwardly into tightly assembled relation.

4. In a rotary brush, the combination of a pair of complementary inner hub members having outstanding flanges disposed in abutting relation, a pair of complementary outer hub members surrounding said inner hub members and having inturned abutting flanges, said inturned flanges being adapted to abut at their end portions against said inner hub members and said outstanding flanges being adapted to abut at their end portions against said outer hub members, a plurality of bristle-holding rings carried on said outer hub members and including radially extending bristles, and means for retaining said bristle-holding rings on said hub in axially-compressed relation.

In testimony whereof I affix my signature. 100
IRISIL L. G. CORNELL.
